2,404,807

VENTILATED WINDOW

Otto Kubatzky, St. Louis, Mo., assignor of one-fourth to Frank W. Watkins, Cleveland, Ohio

Application September 24, 1943, Serial No. 503,699

6 Claims. (Cl. 98—88)

1

The present invention relates to improvements in window constructions and the primary object of the invention is to provide a window sash having a fixed upper glazed portion and a movable lower shield portion forming a closure for the lower portion of the sash and capable of being disposed in various adjusted open positions with respect to the upper fixed portion for ventilating purposes, the entire sash structure capable of being readily mounted in a window frame of simple and inexpensive construction.

A further object of the invention is to provide a window which is devoid of sash cords and weights, and one wherein ventilation may be obtained without objectionable drafts entering the room.

A further object resides in the novel arrangement whereby the rockable and slidable ventilating shield will provide a weather tight construction when in closed relation in the sash.

A still further object resides in the novel means for screening the lower portion of the sash against entrance of insects when the shield is open, and permitting ready cleaning of the upper fixed glazed portion of the sash.

A still further object is to provide a window sash of this character having an open lower portion closed by a rockable and removable shield portion which is also capable of being slid into overlying relation to the fixed upper portion of the sash.

Other objects and advantages of the invention will appear in the following detailed description, taken in connection with the accompanying drawings, forming a part of this specification, and in which drawings—

Figure 1 is a plan view looking at the inner side of the improved window sash with the ventilating shield in a closed position in the lower portion of the sash.

Figure 2 is a side view of the window sash shown mounted in a window frame construction and with the ventilating shield opened.

Figure 3 is a view similar to Figure 1 but showing the ventilating shield in a raised position in the sash.

Figure 4 is a plan view of the glass deflecting shield.

Figures 5 and 6 are enlarged vertical fragmentary sections on the respective lines 5—5 and 6—6 of Figure 1.

Figures 7 and 8 are fragmentary horizontal sections on the lines 7—7 and 8—8 of Figures 5 and 6 respectively.

2

Figure 9 is an enlarged fragmentary section on the line 9—9 of Figure 3.

Figure 10 is a fragmentary sectional view showing the yieldable keeper means for retaining the ventilating shield in various adjusted positions.

Figure 11 is a broken away view looking at the inner side of the supporting trough for the rock-ing deflecting shield.

Figure 12 is a fragmentary detail section showing one manner of securing the channel mem-bers to the end shields of the ventilating shield.

Figure 13 is a detail horizontal section thru the combined screen member and storm sash.

In the drawings and wherein like reference characters designate corresponding parts thru-out the views, the letter A may generally designate the improved window sash and B a window frame or other casing in which the sash is mounted.

20 The frame or casing B may be suitably mounted in a window or other wall opening C and com-prises a plain rectangular frame or casing of wood or other construction in which the sash A is mounted in any preferred manner.

25 The sash A comprises parallel side rails 6, a bottom rail 7 and a top rail 8. Connecting the side rails 6 substantially midway of their height is a medial or parting rail 9 dividing the sash into upper and lower portions 10 and 11 respec-tively. The upper portion 10 may be termed the fixed or closed portion of the sash and is suitably glazed with glass as at 12, while the lower portion 11 of the sash, below the parting rail 9 may be termed the open portion of the sash and this lower portion of the sash is provided with a rockable and slidale ventilating shield 14 and a screen member 15.

Referring now to the construction and ar-rangement of the closure forming ventilating shield 14, the same comprises a glass deflecting shield 16 provided along its side edges with metal channel members 17 which embrace the ends of the shield and have triangular end flange por-tions 18 and 19 embracing the cut away corner por-tions of the glass shield. Extending inwardly in line with the web of each channel member 17 is a locking tongue or rib 20 which extends thru-out the length of the channel. Associated with each end of the shield 16 is an end shield or wing 21 of segmental shape having an arcuate upper edge provided with notches 22, and provided along its outer edge with a right angular stop flange 23. These end shields 21, as shown in Figures 5, 7 and 8, overlie the confronting faces of the side rails 6 between the bottom rail 7 and parting

rail 9 of the sash. As shown also in Figures 7 and 8, the side rails 6 are rabbeted as at 24 to receive the stop flange 23 and limit inward rocking of the shield 14.

Secured along the inner edge of each end shield or wing 21 is a channel member 25 including a U-shaped portion which embraces the edge of the wing, and these channel members may be secured to the wings by striking lugs from the flanges of the U-shaped portion into the wing as at 26 in Figure 12.

Extending inwardly from the inner side of each channel member 25 are flanges 27 and 28 which form guides for the ends of the shield 14 to slide in. The flange 28 along the inner edge of the wing 21 is of L-shape and has its free edge directed toward the flange 27 to form a slot for receiving the tongue 20. Extending from the outer side of each channel member 25 is an L-shaped flange 29 forming a slot into which the inner edge of a facing plate 30 extends when the shield is closed as in Figures 7 and 8. These facing plates 30 extend along the confronting faces of the side rails 6 between the bottom rail 7 and parting rail 9. The side rails 6 are rabbeted as at 31 to form a slot into which the flange 29 extends when the shield is closed. This interfitting of the plate 30 and flange 29 renders the assembly draft proof when the shield is closed.

Secured to the bottom rail 7 with its ends extending into the lower ends of the rabbets 31 is a trough 32 in which the ventilating shield 14 is rockably supported. This trough 32 may be formed from sheet metal and includes a bottom wall 33, a vertical wall 34 along the outer edge of the bottom wall, and a divergent wall 35 along the inner edge of the bottom wall. The wall 34 terminates short of the ends of the trough to accommodate the end shields 21 and flanges 27, while the wall 35 extends into the rabbets 31. The ends of the trough are closed by end walls 36. A strip of rubber or other yieldable material 37 may be disposed in the bottom of the trough for the glass shield 16 to rest upon and form a weather tight arrangement.

Recessed into the inner face of the parting rail 9 is a rubber or felt cushioning and sealing strip 38 against which the shield 16 abuts when in a closed position. Thus, when the shield 16 is closed, the same is sealed at its upper and lower ends by the strips 38 and 37 respectively, and along each side edge by the interfitting of the plate 30 and flange 29. Secured to the under side of the parting rail 9, adjacent each end of the rail, is a keeper 39 each having a spring urged ball normally urged against its adjacent end wing 21 and adapted to engage in the notches 22 for retaining the ventilating shield in various adjusted positions. A handle 40 is secured to the upper flange portion 18 of each channel member 17 by means of a screw or the like 41, and these screws also serve to clamp the members 17 to the glass shield. These handles 40 serve as pulls for rocking the shield.

Secured to the lower flange portion 19 of each channel member 17 is a lift handle 42. These handles 42 are secured by screws 43 which also serve to clamp the members 17 to the glass shield. The cut-away corner portions 16, shown in Figure 4, at the lower edge of the shield 16, together with the flange portions 19, provide chambers for receiving sliding lock bolts 44 normally urged toward the ends of the shield by springs 45 enclosed in the handles 42. These bolts 44 extend thru openings in their respective channel mem-

bers 17, and when the shield 14 is in a closed position, have their ends projected thru the end shields 21 and into openings 46 in the side rails 6. Thus the bolts 44 serve to lock the shield 14 against sliding and rocking movement. Suitable handles 47 serve for operating the bolts 44.

Secured in each of the inner rabbets 31 of the side rails 6 in alignment above each of the channel members 25 is a guide channel 50. These guide channels are open at their confronting sides and are adapted to slidably receive the channel members 17 of the deflecting shield 16 when the shield is raised in the sash as in Figure 3, into overlying relation to the glazed upper portion of the sash. These guide channels are formed with grooves 51 in which the ribs 20 slide and prevent lateral shifting of the shield, as shown in Figure 9. When the shield is in a raised position, the bolts 44 are projected into openings 53 in the side rails 6 for retaining the shield raised.

Thus the ventilating shield 14 may be rocked in the trough 32 for controlling the air entering thru the lower open portion of the sash, and the deflecting shield 16 may be slid upwardly in the sash to provide a fully open lower sash portion. It will be observed that the shield 16 slides in the end wings 21 upwardly into the guide channels 50.

Referring now to the screen member 15, the same is mounted in the lower open portion 11 of the sash between the end wings 21 of the ventilator shield so as to swing outwardly of the sash. The screen member 15 comprises a frame 55 fitting in the outer side of the sash A and disposed entirely within the plane of the sash, as shown in Figure 5. The upper rail of the frame 55 fits in a rabbet formed in the under side of the parting rail 9, while the lower rail of this frame fits in a rabbet formed in the upper side of the bottom rail 7 of the sash. One side rail of the screen frame carries hinge eyes 56 at the outer side of the rail for receiving hinge pins 57 provided on hinge plates 58 secured to the sash rails 7 and 9. The top and bottom rails of the screen frame, adjacent to the opposite side rail, are provided with spring latches 59 having latch bolts adapted to be projected into latch openings 60 provided in the sash rails 7 and 9 for retaining the screen member in a closed position in the sash opening. A suitable screening 61 such as screen wire or the like, is secured over the outer side of the frame 55 as by a wire retainer 62.

The screen member 15 is also adapted to serve as a storm sash when desired by the insertion of a pane of glass 63 into the frame. The frame 55 is provided at the inside of its marginal rails with an inwardly opening channel 64 in which is disposed a sealing strip 65, such as of rubber, felt or the like, and against which the glass 63 seats and is removably retained as by means of suitable retaining means 66.

As shown in Figures 7 and 8, the screen member 15 is disposed between the end shields 21 so that these shields may pass between the ends of the screen member and the side rails of the sash frame upon rocking of the ventilating shield. As shown in Figure 6, the end shields 21 are of such width at their lower portions as to extend between the ends of the screen and sash side rails and thus close the space between the ends of the screen and the sash side rails.

Thus when the ventilating shield 14 is in a lowered position, as in Figures 1 and 2, the shield may be rocked to provide various degrees of ventilation, and when the deflecting shield 16 is in a raised position as in Figure 3, full ventilation

may be had thru the lower portion 11 of the sash. Also, when the shield 16 is raised, in the screen member 15 may be swung out to permit ready cleaning of the outside of the upper glazed portion 10 of the sash.

While the channel members 25 have been shown as metal members secured to the inner edges of the end wings 21, which are preferably formed of a suitable plastic material, these channel members 25 may also be formed of a plastic material and made as an integral part of the end wings. Likewise, various other portions of the structure may also be formed of plastic materials whenever such is found practical and desirable.

Changes in detail may be made to the form of the invention herein shown and described, without departing from the spirit of the invention or the scope of the following claims.

I claim:

1. In a window construction, a sash comprising a frame having top and bottom rails, side rails and a parting rail, said parting rail being provided with a sealing strip of yieldable material extending outwardly of the inner vertical face thereof, a glazed portion above the parting rail, a trough on the bottom rail, a strip of yieldable material in such trough, a deflecting shield rockable upon said strip in said trough with its upper portion closing against said parting rail, guides for the ends of the deflecting shield and rockable therewith, a guide channel on each side rail of the sash frame above said parting rail and with which said guides align when the deflecting shield is closed against the sealing strip, and means for retaining the shield in a raised position in said guide channels.

2. In a window construction, a sash comprising a frame having top and bottom rails, side rails and a parting rail, a glazed portion above the parting rail, a trough on the bottom rail, a strip of yieldable material in said trough, a deflecting shield rockable in said trough upon said strip with its upper portion paralleling said parting rail, an end shield having interlocking engagement with each end of the deflecting shield and providing guides in which the deflecting shield is slideable, said guides movable with the deflecting shield as it is rocked, guide channels on said side rails above said parting rail and into which the shield may be guided to a raised position in the upper portion of the sash, means for retaining the shield raised, and a screen member in the sash frame below said parting rail.

3. In a window construction, a sash comprising a frame including a parting rail and side rails, a facing plate on each side rail below said parting rail, a ventilating shield rockable in the frame including end shields supported by said frame and having interfitting relation when in a closed position with said facing plates, and a deflecting shield slidably mounted in the end shields and rockable on the frame, guide channels in the sash frame above the parting rail for slidably receiv-

ing the deflecting shield in a raised position in the sash frame, and means for retaining the shield in a raised position in the sash, said end shields being movable inwardly of the window on inward tilting of the deflecting shield.

4. In a ventilated window, a sash frame comprising top and bottom rails, side rails, and a parting rail, a ventilating shield rockable on said bottom rail including a deflecting shield provided with a channel member along each of its side edges, each of said channel members having a locking tongue extending inwardly in line with the web portion of its channel member, and end shields movable thru the sash frame beneath the parting rail, means slidably retaining the deflecting shield in the end shields including guide channels adapted to receive said channel members and having grooves adapted to receive said locking tongues, guide channels on the side rails of the sash frame for slidably receiving the deflecting shield in a raised position in the sash frame said second named guide channels having grooves adapted to receive said locking tongues, and locking means for retaining the deflecting shield in a raised position.

5. In a window construction, a sash comprising a frame divided by a horizontal parting rail into upper and lower portions, glazing for said upper portion and including side rails, a ventilating shield rockable in said lower portion including end shields having guide channels along their inner edges, a flange extending from the outer side of each of said channels transverse to the plane of the sash frame, and a deflecting shield mounted at its ends in the guide channels, a facing plate extending along the face of each side rail below the parting rail and each plate interfitting with the said flange of the adjacent channel, means for retaining the ventilating shield in adjusted positions of rocking movement, guide ways inwardly of the glazed upper portion and with which said guide channels align when the ventilating shield is in a closed position.

6. In a window construction, a sash comprising a frame having top and bottom rails, side rails and a parting rail, said parting rail being provided with a sealing strip of yieldable material, a glazed portion above the parting rail, a trough on the bottom rail, a strip of yielding material in said trough, a deflecting shield rockable upon said strip in said trough with its upper portion closing against said parting rail, end shields on the side rails aforesaid having guides for the ends of the deflecting shield and rockable therewith, the deflecting shield being slideable in the guides of the end shields, a guide channel on each side rail of the sash frame above said parting rail and with which said end shield guides align when the deflecting shield is closed against the sealing strip, and means for retaining the deflecting shield in a raised position in said guide channels.

OTTO KUBATZKY.
